Patented Mar. 9, 1920.

UNITED STATES PATENT OFFICE.

HARVEY J. WARNER, OF TAKOMA PARK, DISTRICT OF COLUMBIA.

EXERCISER.

1,333,005.

Specification of Letters Patent.

Patented Mar. 9, 1920.

Application filed June 14, 1919. Serial No. 304,270.

To all whom it may concern:

Be it known that I, HARVEY J. WARNER, a citizen of the United States, residing at Takoma Park, District of Columbia, have 5 invented a new and useful Exerciser, of which the following is a specification.

This invention has reference to exercisers, and its object is to provide a device which may be carried by the hand of the user and 10 manipulated in such manner as to provide for the use of the muscles of the arm and chest and more remotely of muscles of the whole body.

The invention comprises a member which 15 may be readily held by the hand of the user and another member susceptible of rotating about the first member in suitably spaced relation thereto and so related to the grasped member that the inertia effect 20 of the rotated member requires the exercise of muscular effort to hold the inertia member in the desired course, thus bringing into play many of the muscles of the hand, forearm, upper arm, chest, and to an extent 25 many of the muscles of the whole body.

In the practical embodiment, the invention includes a handle member carrying a ring-shaped support for another ring-shaped member, with an offstanding portion 30 in turn carrying an inertia member at a suitable distance from the axis of rotation of the inertia member about the handle. The inertia member may be given a circular motion by an appropriate movement of the 35 hand and arm with the speed of movement demanding more or less effort to hold the inertia member in its proper course, and this exertion imparts exercise to the body of the user with the exercise beneficial. The 40 exerciser is susceptible of use in various ways whereby to cause the effort of operation to effect the muscles in one way or another to the ultimate strengthening of the muscles and the general benefit of the 45 person exercising.

The invention will be best understood from a consideration of the following detailed description taken in connection with the accompanying drawing forming part of 50 this specification, with the understanding, however, that the invention is not confined to any strict conformity with the showing of the drawing, but may be changed and modified so long as such changes and modifications mark no material departure from

the salient features of the invention as expressed in the appended claims.

In the drawing:

Figure 1 is an elevation of a structure embodying the invention. 60

Fig. 2 is a section on the line 2—2 thereof.

Fig. 3 is a section similar to that of Fig. 2 but taken through another form of the invention and omitting the handle portion. 65

Fig. 4 is a section similar to Figs. 2 and 3 but showing still another form of the invention.

Fig. 5 is a section through the handle end of the exerciser, but illustrating some variations in the arrangement of Fig. 4. 70

Referring to the drawing, and particularly to Figs. 1 and 2, there is shown a handle 1 extending diametrically across a ring 2, the handle being appropriately shaped to be grasped by the hand of the user, which hand is then encircled by the ring 2. The handle 1 may be made either actually or effectively in one piece with the ring 2, although this is not obligatory. Formed in the outer periphery of the ring 2 is a groove 3 extending wholly about the ring and constituting one member of a race for antifriction balls 4. Surrounding the ring 3 is another ring 5 having a ball-race 6 about its inner circumference, the two 80 rings being held together by a circular series of the balls 4 which not only form an anti-friction bearing for the movement of the ring 5 about the ring 2, but also lock the two 85 rings together. 90

Projecting from the outer periphery of the ring 5 is an arm 7, the direction of projection being preferably, though not necessarily, radial. The arm 7 is shown as hollow or tubular and internally screw-threaded to receive one end of a threaded stem 8, the other end of which carries an inertia member 9 shown as in the form of a ball, but it is to be understood that such particular form is not obligatory. Furthermore, the ball 9 is indicated as provided with a covering 10 which may, by preference, be of soft rubber, or any other suitable material designed to prevent injury in case the inertia member strikes anything. 95 A lock nut 11 applied to the stem 8 serves to lock the stem in any adjusted position so that the ball 9 may be located at different distances from the handle 1. The bore of the arm 7 is continued through the ring 5 so 100 105 110

as to open into the ball race-way in the ring 5, whereby the ring may be filled with balls through the arm 7 and then the balls are prevented from escaping or jamming by a screw plug 12 introduced into the arm 7 to a point sufficiently close to the balls to prevent jamming thereof.

With an exercising device such as shown in Figs. 1 and 2, the hand of the user grasps the handle 1 with the ring 2 arranged transversely of the length of the arm, or by bending the wrist the ring 2 may be made to assume another angular relation to the length of the arm. Now by imparting a swinging movement, especially about an axis coinciding with the shoulder joint, the inertia member 9 is caused to orbitally move about the handle 1 and the hand grasping the handle. The inertia of the ball 9 tends to impart to it tangential movements and if the orbital movements be rapid the tangential tendency will become pronounced, so that a considerable muscular effort must be exerted to maintain the orbital movements of the inertia member and to keep the bodily movements of the whole device within a reasonably small circular path. If the ring 2 be so held that the orbital movements of the ball 9 approach parallelism with the length of the user's arm, certain muscles will come into play which were not affected by the movements of the inertia ball in planes substantially perpendicular to the length of the arm. The device is susceptible of use in various ways and may be easily manipulated in different manners to affect many muscles of the arms, chest, back and lower portions of the body, and even of the neck.

The exercising device may be made with the stem carrying the inertia member more or less elastic to give a certain amount of elasticity with a corresponding effect and change of exertion on the part of the person exercising. Moreover, the structure may be made in a less elaborate manner than shown in Figs. 1 and 2. In Fig. 3 the arm 7 and stem 8 are replaced by a flexible stem 13 which may be made of a group of elastic wires and these wires may or may not be covered by an envelop 14 in the form of a rubber or other suitable tube. The group of wires forming the stem 13 passes diametrically through a ball 9^a constituting the inertia member and at the outer end are spread so as to hold firmly in the ball and prevent retraction. Of course other means of anchoring the wires in the ball may be employed. At the other end the stem is anchored in a ring 5^a corresponding to the ring 5 of the structure of Fig. 1. This anchoring is performed by passing the inner end of the stem partly through a boss 7^a corresponding to the arm 7 of Fig. 1, but much shorter and opening into a race-way 6^a corresponding to the race-way 6 of the

structure of Fig. 1. A plug 15, of lead or the like, may be used to hold the inner end of the stem 13, the wires of which were held in the ring 5^a being spread to prevent retraction or loosening.

To permit the introduction of balls into the race-way an opening 16 is formed at any convenient point in the ring 5^a and is closed by a plug 17 introduced after the balls have been properly lodged in the race-way. It will be understood that the structure of Fig. 3 is provided with a handle member and ring like the parts 1 and 2 of Figs. 1 and 2. It will be further understood that the inertia member or ball 9^a may have a soft protecting surface like the surface 10 as shown in Figs. 1 and 2, or such surface may be omitted if desired.

The structures of Figs. 1, 2 and 3 are susceptible of considerable elaboration, representing corresponding cost of production. To provide a cheaper, though in many respects equally as effective, structure, the cost of production may be materially reduced along the lines shown in Figs. 4 and 5. In Fig. 4 there is shown a handle 18 similar in shape to the handle 1 of Figs. 1 and 2 and somewhat differently constructed, and this handle is made separately for cheapness of construction. Surrounding the handle 1 is a ring 19 which may comprise a trough shaped or channel strip of metal bent into ring form and provided with radially outward flanges 20. The strip 19 where the ends meet overlaps, as indicated at 21, and one of two screws 22 holding the handle 18 and ring 19 together may be made to traverse the overlapping portion and so secure the overlapping meeting ends of the ring together. Seated in the channel thus formed by the flanges 20 is a metal strip 23 encircling the channel strip 19 and having prolonged meeting ends 24 secured together at intervals by rivets 25 or in other appropriate manner, the prolongations 24, when riveted together, constituting a stem 26 corresponding to the stems 8 and 13 of Figs. 1, 2 and 3. The outer extremities of the prolongations 24 are appropriately bent in opposite directions, as shown at 27, to combine into an embracing clip partially encircling a ball 9^b and a rivet 28 traversing the ball 9^b diametrically and extending through the extremities 27 constitutes a convenient means for securing the parts together. The handle 18 is formed at the ends with wings 29 of sufficient length to receive between them the ring 19 and the flanges 20 so that the screws 22 are not subjected to any twisting strain during the operation of the device. In Fig. 5 the handle portion and the ring carried by the handle are shown as stamped out of sheet metal. For this purpose two identical stampings are provided, each comprising one-half of a handle member 9^c and one-

half of a ring 19^a with side flanges 20^a, the two halves being connected by rivets 30 passed through the handle sections. The structures of Figs. 4 and 5 are designed for cheap production to permit sale at a relatively low price and much lower than would be the case with the structures of Figs. 1, 2 and 3 and especially with respect to the structure of Figs. 1 and 2 where provision is made for the adjustment of the effective length of the stem 8 to vary the distance of the ball or inertia member 9 from the handle 1. However, the usefulness of the structures of Figs. 4 and 5 is very similar to that of Figs. 1, 2 and 3 when considered as exercisers, the principal difference, aside from the question of cost, being in the greater ease of movement with the structures of Figs. 1, 2 and 3 over the structures of Figs. 4 and 5.

20 What is claimed is:—

1. An exercising device comprising a handle adapted to be grasped between the ends by the human hand, and an inertia member carried by and mounted to rotate orbitally about the handle member with the latter transverse to the axis of rotation.

2. An exercising device comprising a handle adapted to be grasped between its ends by the human hand, and provided with a ring-shaped member carried by the handle and to which the latter is diametrically disposed, and an inertia member eccentrically mounted with respect to and rotatable about the ring-shaped member, whereby the inertia member may be caused to move orbitally about an axis transverse to the length of the handle.

3. An exercising device comprising a handle adapted to be grasped between the ends by the hand of the user, a ring-shaped portion carried by the handle member with the latter extending diametrically across the ring-shaped member, another ring-shaped member encircling the first-named ring-shaped member and rotatable thereabout, and an inertia member connected to the second-named ring-shaped member in eccentric relation thereto.

4. An exercising device comprising a ring-shaped member having means extending across the ring-shaped member for grasping by the hand of the user, another ring-shaped member encircling the first ring-shaped member and secured thereto for rotative movement circumferentially about the first ring-shaped member, and an inertia member connected to and spaced away from the second-named ring-shaped member in substantially radial relation to the axes of rotation of the second-named ring-shaped member about the first ring-shaped member.

5. An exercising device comprising two ring-shaped members in concentric relation, with the inner ring-shaped member provided with a handle adapted to be grasped by the

hand of the user and extending diametrically across said ring-shaped member, and an inertia member having means for securing it to the second-named ring-shaped member and projecting in a substantially radial direction from said second ring-shaped member. 70

6. An exercising device comprising two concentrically related ring-shaped members, a handle secured to the inner member and extending diametrically thereacross, a stem projecting in a substantially radial direction from the outer member, and an inertia member carried by the outer end of the stem. 75

7. An exercising device comprising two concentrically related ring-shaped members, a handle secured to the inner member and extending diametrically thereacross, a stem projecting in a substantially radial direction from the outer member, and an inertia member carried by the outer end of the stem, the meeting faces of the two ring-shaped members being provided with ball raceways, and a series of antifriction balls lodged in the raceways and holding the two members 90 against lateral displacement one with respect to the other. 85

8. An exercising device comprising a ring-shaped member with a handle adapted to be grasped by the hand of the user extending diametrically across the ring-shaped member, and said member having an outer peripheral raceway, another ring-shaped member encircling the first-named member and provided with an inner peripheral raceway, and also provided with an interiorly threaded arm projecting radially from said member, a series of antifriction balls lodged between the two members in the raceways, a screw stem entering the threaded arm and 105 adjustable lengthwise of the latter, and an inertia member carried by the outer end of the threaded stem. 95

9. An exercising device comprising a ring-shaped member with a handle adapted to be 110 grasped by the hand of the user extending diametrically across the ring-shaped member and said member having an outer peripheral raceway, another ring-shaped member encircling the first-named member and provided with an inner peripheral raceway, and also provided with an interiorly threaded arm projecting radially from said member, a series of antifriction balls lodged between the two members in the raceways, a screw 120 stem entering the threaded arm and adjustable lengthwise of the latter, and an inertia member carried by the outer end of the threaded stem, said inertia member having an exterior covering of yieldable material 125

serving as a protector.

10. An exercising device comprising an inertia member, a mounting therefor about which the inertia member is rotatable, and from which it is offset in a direction radial 130

to the axis of rotation, and a handle carried by the mounting crosswise of the axis of rotation.

11. An exercising device comprising a ring-shaped member of channel cross section, a diametrically located handle secured thereto, another ring-shaped member surrounding the first-named member and hav-

ing a stem projecting radially therefrom, and an inertia member secured to the outer 10 end of the stem.

In testimony, that I claim the foregoing as my own, I have hereto affixed my signature.

HARVEY J. WARNER.
